CLAIM

The ornamental design for a telescoping dispenser for cotton balls or the like.

DESCRIPTION

FIG. 1 is a top plan view of a telescoping dispenser for cotton balls or the like embodying my new design;

FIG. 2 is a side elevational view;

FIG. 3 is a bottom plan view; and

FIG. 4 is a sectional view along line 4—4 of FIG. 1 with cotton balls being shown in broken lines to show environmental use only.

FIG.1

FIG.3

FIG.2

FIG.4
